UNITED STATES PATENT OFFICE.

ERNST G. K. ANDERSON, OF CHICAGO, ILLINOIS, ASSIGNOR TO BENJAMIN ELECTRIC MANUFACTURING COMPANY, OF CHICAGO, ILLINOIS.

SWITCH MECHANISM.

1,031,768.

Specification of Letters Patent.

Patented July 9, 1912.

Application filed August 10, 1909. Serial No. 512,179.

To all whom it may concern:

Be it known that I, ERNST G. K. ANDERSON, subject of the King of Sweden, residing at Chicago, in the county of Cook and State of Illinois, have invented new and useful Improvements in Switch Mechanisms, of which the following is a full, clear, concise, and exact description, reference being had to the accompanying drawing, forming 10 a part of this specification.

This invention relates to improvements in switch mechanism for controlling electric circuits.

The principal object of the invention is to 15 provide switch mechanism which is of simple and economical construction, although efficient and durable, and which both opens and closes the circuit with a snap action, this being usually regarded as desirable in devices for controlling circuits of such potential as is employed in electric lighting.

In the accompanying drawings, I have illustrated my improved switch mechanism as applied first, to a pendant switch such 25 as is employed in connection with cluster sockets and the like.

I have also shown my invention as applied to two slightly different forms of wall switch adapted to be operated, in the first 30 of these two forms, by the throwing over of a lever, and in the second form by the manipulation of a pair of push buttons projecting from the under side of the casing of the device.

In these drawings, Figure 1 is a perspective view of the pendant switch device complete; Fig. 2 is a plan view of the same with the cap which normally conceals the binding screws and the upper side of the base which 35 carries these binding screws and certain other parts, removed; Fig. 3 is a longitudinal sectional view of this device, the section being taken on the line 3—3 of Fig. 2 looking in the direction of the arrows; Fig. 4 is a longitudinal sectional view of the same, the section being taken on the line 4—4 of Fig. 2, looking in the direction of the arrows; Fig. 5 is a perspective view of the movable switch blade of the device; Fig. 50 6 is an elevational view of the metal blank from which the switch blade is formed; Fig. 7 is a perspective view of the blade-operating member; Fig. 8 is an elevational view of the blank from which this member 55 is formed; Fig. 9 is a perspective view of

the form of wall switch in which the switch blade is actuated by moving a lever; Fig. 10 is an elevational view of the same with the cap or cover removed; Fig. 11 is a perspective view of that form of the device in 60 which the switch blade is actuated by the manipulation of a pair of buttons or push rods projecting from the bottom of the casing; Fig. 12 is an elevational view of the same with the cover removed; Fig. 13 is a 65 perspective view of the stationary switch contacts which are bridged by the switch blade when the switch is closed; and Fig. 14 is a perspective view of the switch blade.

In the several figures of the drawings 70 like reference numerals indicate the same parts throughout.

Referring first to that form of the invention shown in Figs. 1 to 8 inclusive, which illustrate the pendant switch, 15 is an insulating base formed of porcelain or other suitable material and inclosed in an acorn-shaped casing shell 16 provided with a cap 17 which telescopes over the upper end of the shell 16 and is formed with a central 80 opening provided with an insulating bushing 18 through which enter the lead wires 19, 19. The insulating base 15 is formed with an elongated rectangular recess 20 which extends up into the base from the 85 lower end thereof and contains the movable parts of the switch mechanism as well as the stationary switch contacts.

The switch blade 21 is formed of a strip of metal cut as shown in Fig. 6 and bent over upon itself on the dotted lines so as to form a rectangular expanded portion 22 which, when the parts are assembled, is arranged to be moved in between the stationary switch contacts and bridge the same. 95 This metallic strip has one of its ends perforated at 23 and its opposite end bifurcated to form two legs 24 with foot-like portions 25 at their ends. When the strip is bent to the form shown in Fig. 5 the legs 24 extend down on each side of the aperture 23 and are adapted to be sprung toward each other against their tendency to remain separated. A pin 26 extends through the aperture 23 and forms a pivot on which turns the switch blade member. This pin 26 extends laterally from the recess 15 through a channel 27 and is bent upward, passing up through the base into a depression 28 in the upper end of the base. A pair of 100

nuts 29 and 30 screw upon the upper threaded end of the pin to hold the same in place. Pivoted on the pin 26 is a blade actuating member formed of sheet metal 5 cut as shown in Fig. 8 and bent to the form shown in Fig. 7. This member, when formed ready for insertion into the chamber of the device, has a substantially rectangular body part 31 having an aperture 10 32 through which the pin 26 extends, a pair of upturned arms 33, and a downwardly extending tongue 34. The tongue 34, when the parts are assembled, carries secured thereon an insulating finger piece 35 which 15 extends through a slot 36 formed in the bottom of the acorn-shaped casing shell 16. In operating the device to open and close the switch the finger piece 35 is moved to one side or the other in the slot 36 and 20 causes the blade 22 to move with a snap action from one end of the chamber 20 to the other, as explained hereinafter.

When the parts are assembled the feet 25 on the switch blade member occupy a 25 position between the arms 33 of the blade-operating member, the inner edges of which form slideways for sliding engagement with the feet 25, and when the finger piece carried by the latter is at one end or the other 30 of the slot in which the same moves the feet are permitted to spread away from each other. When, however, the member 35 is pushed toward the opposite end of the slot the feet are made to approach each other because the distance between the arms 33 on 35 a line extending directly across these arms at right angles therewith is less than the distance normally existing between the feet. As soon, however, as the operating member 40 reaches a position at which the feet do not coincide in position with a line drawn at right angles with the arms 33 these feet are permitted to spread apart and, in effect, slide down retreating inclined planes formed 45 by the slideways on the inner edges of the arms. It will be seen that this motion will be accomplished quickly and immediately after the actuating member 35 has reached and passed slightly beyond such a position 50 that the actuating member and the switch blade are in direct alinement with each other. The upper part 22 of the switch blade member, when the device is in the "on" position, passes in between two stationary contact members 37 and 38, each of 55 these members comprising a metallic L-shaped strip which extends upward through a suitable aperture in the base, the upper ends of these strips extending away from 60 each other and being each clamped under a terminal plate 39. The plates 39 are held in position by means of screws 40 which extend up through the base, the contact plates and the terminal plates 39. Each 65 terminal plate 39 carries a binding screw

41 to which are led the wires which are to be brought into electrical communication with each other by the closing of the switch. When the operating finger 35 is thrown to the right, as seen in Fig. 4, the switch blade 70 22 also passes to the right and moves in between the contact plates 37 and 38 and, by bridging the same, makes electrical connection between the wires 19. When the operating finger is moved over to the opposite 75 position, or to the left hand end of the slot, the switch blade member moves in the same direction and passes out from between the contact plate and breaks the circuit. In Figs. 9 and 10 this form of switch blade 80 actuating means is shown as applied to a wall switch. In this device a base 42 of insulating material is mounted upon a suitable back plate 43 and is provided with apertures 44 through which enter the wires 85 which lead to the binding screws 45 and 46. Each of these binding screws is carried by an L-shaped plate, these plates being designated 47 and 48. The plates 47 and 48 constitute the stationary contact points of the 90 switch and are insulated from each other and rigidly supported in position in the manner illustrated in Fig. 13. Mounted upon the base 42 is a strip of insulating material 49 upon which rests the L-shaped 95 plate 48, this plate being held in place by a screw 50 and having its end 51 arranged to extend toward the movable switch blade and curved slightly outward to permit the same to pass in between it and the corresponding end 53 of the other plate 47. This second L-shaped plate rests upon an insulating block 54 which lies upon the plate 48 and insulates, as well as spacing, the plates from each other. A screw 55 secures 100 the plate 47 in place.

The switch blade consists of a plate doubled upon itself and having one of its ends bifurcated to form a pair of legs 56, each of which is provided with a foot 57. The 110 switch blade is perforated at 58 for the passage of a pin 59, which pin also extends through and forms a pivot for an actuating plate 60, formed with arms 61 and 62 which embrace between them the feet 57 of the 115 switch blade member as in the construction illustrated in Figs. 1 to 8 inclusive. The actuating plate 60 has a tongue 63 which carries an insulating finger piece 64 arranged to project through a cut-out place 65 120 formed in the edge of the cover or cap 66 which fits upon the edge of the base 42 and conceals and protects the mechanism mounted upon the face of the same. To limit the movement of the actuating plate a pair of 125 stops are provided which may conveniently consist of lugs 67 cast upon the porcelain base and extending outward from the face thereof. A stop 68 is cast upon the porcelain base to prevent the switch blade moving 130

too far when the switch opens, while movement in the opposite direction is limited by the edge of the blade engaging the insulating block 54.

It will be seen that when the actuating finger piece 64 is moved to such a position as to bring the operating plate 63 and switch blade member into alignment with each other the feet carried by the latter are forced toward each other, as already described in connection with the pendant form of switch. As soon as the actuating plate passes slightly beyond this point the tendency of the feet to separate causes the switch blade to move suddenly upon the pivot 54 in the same direction as that in which the finger piece is being moved, the feet sliding down the inclined planes formed by the inner edges of the arm 61 and spreading apart.

To provide a good engaging surface having considerable length at the edges where the circuit breaks and where the tendency to sparking would occur I provide upon each side of the switch blade member an ear 69, these ears being bent forward and extending slightly beyond the front surface of the switch blade member. These ears are slightly greater in width from front to back than the distance which normally exists between the stationary contact members 51 and 53, so that when they are thrust in between the latter the same separate lightly and bear with elastic pressure upon the ears and make good electrical connection therewith.

In Figs. 11 and 12 I have shown this form of switch mechanism applied to a wall switch having a pair of buttons or push rods extending therefrom, one of which is black and the other white. By pressing the white button upward the switch is made to close and the black button descends, while pressing the black button upward causes the switch to open and the white button to descend. The switch contacts 47 and 48 are similar in construction and arrangement to those already described in connection with Figs. 9 and 10. The switch blade is also similar to that shown in Fig. 10, but the actuating plate is modified to adapt it to the use of push rods instead of the lever used in Fig. 10. The switch actuating plate in this instance comprises a flat bar 70 having its ends apertured for the passage of pins or the like 71 by means of which a flat strip 72 is hinged to each end of the bar 70. The bar 70 is provided with a pair of tongues which extend laterally from the lower edge thereof and are bent over upward to form arms 73 corresponding in function to the arms 61 and 62 of the form illustrated in Fig. 10 and the arms 33 of the pendant switch form shown in Fig. 4. The plate 70 is pivoted upon a pin 74 upon which is also pivoted the switch blade member.

Each of the push buttons comprises a short rod formed of insulating material extending downward through notches formed in the lower edge of the cover 75. The right hand rod 76 may be of porcelain or other white or light colored material, while the left hand rod 77 may be of black hard rubber. These buttons are secured by means of rivets or the like to the plates 72.

Having thus described my invention, what I claim as new and desire to secure by Letters Patent, is:

1. In electric switch mechanism, the combination of a switch blade, a pair of resilient members carried thereby and tending to move away from each other, an actuating member pivoted between said resilient members and on an axis common to the axis of the switch blade, a pair of arms carried by said actuating member and disposed to embrace said resilient members between them, said arms having engaging surfaces for making sliding engagement with said resilient members, said engaging surfaces extending parallel with each other, and means for moving said actuating member about its pivot.

2. The combination of a switch blade portion and an actuating portion pivoted on a common axis, one of said portions having a pair of resilient portions, the other of said members having a pair of arms arranged to embrace said resilient members, said arms having surfaces engaging said resilient members and extending parallel with each other, the distance between said engaging surfaces being less than the normal distance between said resilient members, whereby the tendency of said resilient members to move away from each other causes the switch blade portion to move to an angular position with relation to said actuating portion when the latter has been moved upon its pivot past a given position with relation to said switch blade portion.

3. In electric switch mechanism, the combination of a switch blade member, an actuating member, resilient arms on one of said members, and means on the other of said members arranged for sliding engagement with said arms, said arms and said engaging members coöperating to move said switch blade member into angular relation with said actuating member when said actuating member has been moved beyond a predetermined position with relation to said switch blade member.

4. In electric switch mechanism, a switch blade member consisting of a pivoted strip of metal having the end thereof remote from the pivot bifurcated to form a pair of spring fingers and bent upon itself so that said spring fingers extend toward the pivot, and a pivoted actuating member for said switch blade, said actuating member being

provided with means for distorting said spring fingers when it is rocked about its pivot, for the purposes set forth.

5. In electric switch mechanism, a switch blade comprising a strip of metal having an aperture near one of its ends and having its opposite end bifurcated and bent over upon its apertured end, a pivoted actuating member having a pair of slideways thereon embracing the parts of said bifurcated end of

said switch blade, and means for pivoting said switch blade at said aperture.

In witness whereof, I have hereunto subscribed my name in the presence of two witnesses.

ERNST G. K. ANDERSON.

Corrections in Letters Patent No. 1,031,768.

It is hereby certified that in Letters Patent No. 1,031,768, granted July 9, 1912, upon the application of Ernst G. K. Anderson of Chicago, Illinois, for an improvement in "Switch Mechanism," errors appear in the printed specification requiring correction as follows: Page 3, line 96, for the word "portions" read *members* and same page, line 97, for the word "members" read *portions*; and that the proper corrections have been made in the files and records of this office and are hereby made in the said Letters Patent.

Signed and sealed this 27th day of August, A. D., 1912.

[SEAL.]

F. A. TENNANT,
Acting Commissioner of Patents.

provided with means for distorting said spring fingers when it is rocked about its pivot, for the purposes set forth.

5. In electric switch mechanism, a switch blade comprising a strip of metal having an aperture near one of its ends and having its opposite end bifurcated and bent over upon its apertured end, a pivoted actuating member having a pair of slideways thereon embracing the parts of said bifurcated end of

said switch blade, and means for pivoting said switch blade at said aperture.

In witness whereof, I have hereunto subscribed my name in the presence of two witnesses.
